UNITED STATES PATENT OFFICE.

WILLIAM P. MIZE, OF MESA, TEXAS.

FERTILIZER-DISTRIBUTER.

SPECIFICATION forming part of Letters Patent No. 700,533, dated May 20, 1902.

Application filed June 1, 1901. Serial No. 62,782. (No model.)

To all whom it may concern:

Be it known that I, WILLIAM P. MIZE, a citizen of the United States, residing at Mesa, in the county of Grimes and State of Texas, have 5 invented new and useful Improvements in Fertilizer-Distributors, of which the following is a specification.

This invention relates to fertilizer-distributors; and the principal object of the invention is to provide a fertilizer-distributer in which there is provided in connection with a suitable hopper means for agitating and loosening up the fertilizing material and delivering the same through a series of discharge- 15 openings, such series extending transversely of the path of movement of the machine across the field and controlled by individual and independently - operable feed slides or gates, whereby the machine may be used for simultaneously fertilizing adjoining furrows or as a broadcast fertilizer-distributer.

A further object of the invention is to provide in connection with the fertilizer-hopper a detachable hood or cut-off, which when 25 in place covers some of the discharge-openings and causes all of the fertilizing material to pass to those discharge - openings which are not covered and protected by the hood or cut-off.

With the above and other objects in view, which will appear as the description proceeds, the invention consists in the novel construction, combination, and arrangement of parts hereinafter fully described, illustrated, and 35 claimed.

In the accompanying drawings, Figure 1 is a side elevation of a fertilizer-distributer constructed in accordance with the present invention. Fig. 2 is a plan view thereof. Fig. 40 3 is a vertical cross-section taken through the same, showing the removable hood or cut-off and the transverse series of feed-slides. Fig. 4 is a vertical longitudinal section through the distributer, showing the agitator-shaft, agitators, clearers, and one of the feed-slides. 45

Similar numerals of reference denote like parts in all figures of the drawings.

The fertilizer-distributer contemplated in this invention is designed to be supported 50 upon suitable carrying-wheels 10 and comprises a rectangular frame consisting of longitudinal bars 11 and end cross-bars 12, which

are securely fastened together and supported by means of posts 13 on the axles 14, upon which the carrying-wheels are journaled. 55

In carrying out the present invention I provide a fertilizer-hopper 15, the side walls 16 of which may extend vertically, but the end walls 17 of which are arranged at an angle to slope inwardly and downwardly toward each other, where they terminate in a concaved bottom or trough 18, extending transversely of the machine. The hopper is supported by means of cross-bars 19 of substantially triangular shape in cross-section and resting at 65 their opposite ends upon the longitudinal bars 11 of the main frame.

In the lower portion of the hopper are arranged parallel bars 20, which extend transversely across the frame beneath the main 70 longitudinal bars 11, to which they may be secured; if desired, and said parallel bars form the supporting means for the bottom or trough 18, which is provided with oppositely-extending flanges 21, secured to the bars 20 75 by means of bolts or other suitable fasteners 22. The trough 18 extends entirely across the machine and is provided with a series of discharge-openings 23, which are controlled by a segmental feed-slide 24, operating between grooved cleats or guides 25, secured to the bottom of the trough and provided at one end with an operating-handle 26, by means of which each slide may be moved independently of all the other slides for partially or 80 wholly opening and closing the discharge-opening which it controls.

Journaled in suitable bearings connected with the longitudinal bars 11 is an agitator-shaft 27, which passes through the bottom of 90 the hopper and is provided with a plurality of radiating agitating-fingers, some of which are provided with terminal hooks 28 and others of which (indicated at 29) are straight. By preference two sets of hooked fingers 28 95 and one set of straight fingers are provided for and above each discharge-opening, as illustrated in Fig. 3, and when the shaft is rotated said fingers serve to stir, agitate, and loosen up the fertilizing material in a manner which will be readily understood, thereby preventing the material from becoming packed and clogged in the trough and insuring the proper feeding of the same through 100

the discharge-openings. Extending across the top of the shaft 27 is a series of clearers 30, preferably in the form of rods, the opposite ends of which are bent downward and 5 secured to the parallel bars 20, as shown in Fig. 4. These clearers serve to scrape surplus material from the agitator-fingers and maintain the latter in operative condition.

In order to cut off the supply of fertilizing material to the intermediate discharge-openings, I provide a removable hood or cut-off 10 comprising, essentially, parallel side plates or portions 32, having vertical slots 33 to fit over the agitator-shaft 27 and adapted to rest 15 upon the bottom or trough 18 between the outermost discharge-openings and the intermediate discharge-openings, as plainly illustrated in Fig. 3. The side portions 32 are braced relatively to each other by means of 20 a tie 34, and the said hood or cut-off is equipped with a double pitched top or roof 35, which will divide the material placed in the hopper and cause equal parts thereof to pass into the space at opposite sides of the 25 hood, where such material will be operated upon by the agitator-fingers and caused to pass through the outermost discharge-openings 23. In this manner adjoining rows or furrows may be fertilized, or by removing 30 the hood 31 the machine is adapted to distribute the fertilizing material broadcast.

The improvement hereinabove described will be found especially valuable to farmers, as they may be mounted upon a truck or an 35 ordinary farm-wagon after removing the wagon-body. Motion is imparted to the agi-

tator-shaft 27 by means of a chain 36, driven by a sprocket-wheel 37, connected with one of the wheels and passing around another sprocket-wheel 38 on the outwardly-projecting 40 extremity of the agitator-shaft, as clearly shown in the drawings.

I do not desire to be limited to the exact arrangement hereinabove described, and accordingly reserve the right to change, modify, 45 or vary the construction within the scope of the appended claim.

Having thus fully described my invention, what I claim as new, and desire to secure by Letters Patent, is—

In a fertilizer-distributer, the combination with a wheeled truck; of a hopper for the fertilizing material, said hopper being supported on the truck-frame, a concaved trough forming the bottom of the hopper and provided 55 with a series of discharge-openings extending transversely of the machine, an agitator-shaft within the trough, means for driving said shaft, and a cut-off or hood comprising sides which slope transversely of the machine 60 and are provided on their lower edges with vertical slots removably fitted in the central portion of the hopper over the agitator-shaft whereby the centrally-arranged discharge-openings are covered and the fertilizer di- 65 rected toward the end openings.

In testimony whereof I affix my signature in presence of two witnesses.

WILLIAM P. MIZE.
